CLAIM

The ornamental design for a display screen or portion thereof with animated graphical user interface, as shown and described.

DESCRIPTION

FIG. 1 is a front view of a first embodiment showing a first image in a sequence of a display screen or portion thereof with animated graphical user interface;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a second embodiment showing a first image in a sequence of a display screen or portion thereof with animated graphical user interface;

FIG. 9 is a front view of a second image thereof;

FIG. 10 is a front view of a third image thereof;

FIG. 11 is a front view of a fourth image thereof;

FIG. 12 is a front view of a fifth image thereof;

FIG. 13 is a front view of a sixth image thereof; and,

FIG. 14 is a front view of a seventh image thereof.

The appearance of the animated graphical user interface sequentially transitions between the images shown in FIGS. 1-7 and FIGS. 8-14. The process or period in which an image transitions to another image forms no part of the claimed design.

The outer even broken lines showing a device are for the purpose of illustrating environmental structure and form no part of the claimed design. All other broken lines showing the display screen or portion thereof with animated graphical
